COUPLING SYSTEM

Ludwig Walter, Berlin, Germany, assignor to
 Telefunken Gesellschaft für Drahtlose Tele-
 graphie m. b. H., Berlin, Germany, a corporation
 of Germany

Application October 16, 1933, Serial No. 693,716
 In Germany September 30, 1932

4 Claims. (Cl. 250—33)

This invention relates to an improved high or radio frequency cable system by means of which an effective change of circuits can be made without impairing the efficiency of the system.

5 An object of the invention is to provide a circuit arrangement and coupling system adapted to unite at will the downleads of a system comprising a plurality of energy transmission lines with any desired one of the transmission lines 10 or leads of another system of similar nature. Such an arrangement may be used, for example, in receiving equipments for radio intelligence transmission on short waves. Where such systems are extensive, they usually contain a comparatively large number of aerials and also a 15 plurality, but mostly dissimilar number, of receivers, and there arises a practical requirement to connect anyone of the receivers with any desired antenna.

20 A further object of the invention is to terminate a number of electrical lines or cables with a series of separable connectors or socket members so disposed that certain portions thereof are stationary and arranged in such a manner 25 that any one thereof may be engaged by a mating socket attached to one of the lines without change in the length or inductance of said line. Other objects of the invention will become apparent to those skilled in the art as the description 30 thereof proceeds.

One embodiment of the invention is shown in the accompanying drawing in which:

Figure 1 is a side elevation of the coupling system;

35 Figure 2 is a front elevation of the same; and Figure 3 is a cross section of one form of cable which may be employed for the coupling system.

In my application, Serial No. 650,645, filed January 7, 1933, of which this application is a 40 continuation in part, I have disclosed a circuit arrangement which serves to connect selectively radio frequency feed lines comprised in a system consisting of a plurality of such lines, with the lines or down-leads of another system. Such an arrangement is used in equipments and installations where a relatively great number of antennæ is to be connected with a different number of receivers or transmitters. The embodiment disclosed in the above patent application 45 in which the terminal points of the antenna lines and the terminal points of the receiver or transmitter leads are each located upon the periphery of a circle or at the corners or angles of a polygon, is especially well suited in installations in which at both ends there are a relatively

great number of connecting points, and where the number of lines comprised in the two groups do not widely differ from each other.

Now, the present invention contains a suitable arrangement for the case where one group of lines contains but a few, say, 3 or 4 lines or leads, and the other one a considerably greater number, say, from 10 to 20. The flexible connecting wires or conductors constituting the movable circuit means between both groups, according to this 10 invention, are passed over a curved surface to which the lines of one of the systems are brought; the ends of the lines of the other system are disposed upon an evolvent or involute which the 15 ends of the connecting wires hanging down over the said curved surface describe as they are moved.

As shown in the drawing the cables 1 which may run to radio receivers or transmitters are laid adjacently over a narrow drum 2 having a curved 20 surface 6, the drum being suitably supported on a support 7 which, as shown, may be a wall. The ends of the cables passing over the drum have secured thereto the terminal or coupler members 3 which cooperate with the cable heads 4 of the antenna down leads 5. The separable or mating connector or terminal members 3 and 4 may be of any desired type but are preferably of the kind described in my aforesaid application, Serial No. 650,645. The stationary portions 4 of the connectors are arranged upon a curve 8 and held in 25 such position by any suitable supporting means (not shown), the curve 8 being an involute of the curved surface 6 of drum 2. As a result of the described arrangement, each connector 3 is able 30 to reach each of the stationary connectors 4 conveniently and without change in the inductance of the transmission line 1 to which it is connected. The drum 2 is made of sufficient width to accommodate the desired number of cables 1, which 35 may be placed in close proximity to each other and its diameter or radius of curvature is governed by the minimum radius of curvature of the concentric cable parts used as the connecting cables 1. It will be understood that the lower ends of 40 the antenna leads 5 will run to the several antennæ of the system.

The radio frequency cables 1 and 5 may be of the form shown in my aforesaid application, comprising two concentric conductors 31 and 32 separated at intervals along the length of the cable 45 by insulating spacers 33.

Having described my invention, what I claim and desire to secure by Letters Patent is:

1. In combination in a device of the class de- 55

- scribed, a flexible electrical transmission cable having a separable connector secured to one end thereof, a curved surface in contact with a limited portion intermediate the ends of said cable, a plurality of cables each of which is terminated by a connector adapted to engage said separable connector, said terminating connectors being arranged on a curve which is an involute of said curved surface.

10 2. In combination in an electrical transmission system, a plurality of flexible cables each having a separable connector secured to one end thereof, a supporting body having a curved surface in contact with a portion of each of said cables and intermediate the ends thereof, a plurality of stationary connectors adapted to be selectively engaged by any one of said separable connectors and arranged on a curved surface which is an involute of said first named curved surface and an electrical transmission line connected to each of said stationary connectors.

15 3. In a transmission system, the combination of a body having a convex curved surface, means for

10 supporting said body, a plurality of radio frequency transmission cables each having a portion in contact with said curved surface, a terminal connector secured to the end of each of said transmission cables, a plurality of stationary connectors adapted to be selectively engaged by either of said terminal connectors and arranged in the form of a concave curve and a radio frequency transmission line connected to each of said stationary connectors.

15 4. In a transmission system, the combination of a body having a surface in the form of a portion of a cylinder, a plurality of electrical transmission cables engaging said surface and each having a separable connector secured to one end thereof, a plurality of similar terminal connectors arranged on a curved surface under said body and arranged to be selectively engaged by either of said separable connectors, and an electrical conductor connected to each of said terminal connectors.

20 LUDWIG WALTER.

3. In a transmission system, the combination of a body having a convex curved surface, means for

supporting said body, a plurality of radio frequency transmission cables each having a portion in contact with said curved surface, a terminal connector secured to the end of each of said transmission cables, a plurality of stationary connectors adapted to be selectively engaged by either of said terminal connectors and arranged in the form of a concave curve and a radio frequency transmission line connected to each of said stationary connectors.

4. In a transmission system, the combination of a body having a surface in the form of a portion of a cylinder, a plurality of electrical transmission cables engaging said surface and each having a separable connector secured to one end thereof, a plurality of similar terminal connectors arranged on a curved surface under said body and arranged to be selectively engaged by either of said separable connectors, and an electrical conductor connected to each of said terminal connectors. 15 20
